UNITED STATES PATENT OFFICE.

ARTHUR M. LARA, OF MINNEAPOLIS, MINNESOTA.

CARBURETER.

SPECIFICATION forming part of Letters Patent No. 623,321, dated April 18, 1899.

Application filed July 25, 1898. Serial No. 686,780. (No model.)

To all whom it may concern:

Be it known that I, ARTHUR M. LARA, a citizen of the United States of America, residing in the city of Minneapolis, in the county of 5 Hennepin and State of Minnesota, have invented certain new and useful Improvements in Carbureters, of which the following is a specification.

My invention relates to apparatus charging 10 or carbureting air with gasolene or other volatile fluid and forming a fixed gas, and has for its object the provision of apparatus which shall be extremely simple and cheap in construction, positive and efficient in operation, and in which all danger of leakage or 15 explosion is eliminated.

To these ends my invention consists in a suitable gasolene-supply, a supply of air under pressure, and means whereby a stream of 20 air under pressure is brought into conjunction with gasolene, the air being substantially surrounded by gasolene at the point of introduction of gasolene to the air current or stream and thereafter thoroughly admixed and carbureted therewith, suitable means being provided for storing the resultant gas or for drawing off the same as formed.

My invention consists, further, in various other features, combinations of parts, and 30 constructions, all hereinafter fully explained, and particularly pointed out in the claims, and will be more readily understood by reference to the accompanying drawings, forming a part of this specification, and in which—

35 Figure 1 is a perspective view of an apparatus embodying my invention, portions thereof being shown in section to illustrate the interior construction. Fig. 2 is a sectional view taken on line X² X² of Fig. 1, 40 looking in the direction of the arrows. Fig. 3 is a perspective view of my carbureter. Fig. 4 is a sectional view thereof, taken on the line X⁴ X⁴ of Fig. 3 and looking in the direction of the arrows.

45 As shown in the drawings, I provide a suitable air-tight tank composed of the cylindrical shell 2, formed of sheet metal or other suitable material, and two heads 3 4, and is divided into two air-tight compartments or 50 chambers 5 and 6 by the partition 7, as shown

in Fig. 1. This partition is located at about the center of the tank and extends lengthwise thereof nearly to the heads 3 and 4, which form the ends of the tank. The partition 7 is carried down parallel to the head 4, 55 close thereto, leaving only sufficient room between the downwardly-extending part of the partition and the head 4 for the insertion therebetween of a washer or packing-ring 8, for the purpose hereinafter mentioned. The 60 heads 3 and 4 are of cast metal, and the ends of the shell are swelled into them, forming air and water tight joints. Near the bottom of the downward extension of the partition 7 a circular opening is provided in said partition, and into this the screw-threaded end of a pipe 9 is inserted, being screwed thereinto. A suitable packing-ring or washer 8 is then slipped over the pipe 9 and the head 4 slipped over the pipe, which passes through an opening in the head which coincides with the opening in the downward projection of the partition. A jam-nut 10 is then slipped over the pipe 9 and is screwed upon the thread of the pipe until it bears against the boss about the 75 opening in the head 4, thus drawing the head and packing-ring 8 tightly against the partition 7 and making water and air tight joints between the head 4, packing 8, pipe 9, and partition 7. The pipe 9 is connected, as 80 shown, with a pipe leading from the air-compressor. Near the top of the head 4 a pipe 11 is screwed into a threaded opening in the head and a pipe connecting with the service-main connected therewith. I have shown 85 an altitude pressure-gage of common form in connection with this service-pipe, by means of which the pressure of gas may be ascertained.

The partition 7 extends nearly the full 90 length of the tank and is carried down parallel with the head 3 at a sufficient distance therefrom to permit the insertion of a carbureter 20 between the head 3 and the partition 7. Below the carbureter the partition 7 extends at right angles toward the head 3 until close thereto and thence extends down to the inner edge of the shell 2, as shown in Fig. 1. A pipe 12 extends from the chamber 5 through 95 a suitable opening in the partition 7 and 100

through a suitable opening in the head 3, and a packing 8 is interposed between the partition 7 and the head 3 about this pipe 12, and a jam-nut 10 is slipped over the end of the pipe 12 and screwed upon the thread thereof, drawing the head 3 and packing 8 snug up against the partition 7, making an air and water tight joint. A pipe 13 is connected to the pipe 12 by a suitable union 14. The pipe 13 extends for a short distance straight away and thence upward at a right angle to a vertical check 15 of ordinary construction. From thence the pipe 13 extends up a short distance and extends at a right angle toward the tank. A pressure reducer or governor 16 of the ordinary or any preferred construction is provided in connection therewith. A pipe 17 extends from the head 3 and is connected with the pipe 13. The pipe 17 leads into a duct 18, the head being chambered or cored out to form the same. This chamber leads down the head to a point slightly past the center thereof. Near the bottom of this chamber or duct 18 is provided an opening which is screw-threaded, and into this opening the inlet-pipe 19 of the carbureter 20 is screwed. The carbureter 20 is of the form shown best in Figs. 2, 3, and 4, where it will be seen that the inlet 19 opens into a long cylindrical chamber 20', extending the length of the carbureter. A series of ducts 21 lead from the chamber 20' and connect with the pipes 23, inserted into the seat 24, provided therefor at the top of the carbureter. The pipes 23 are preferably soldered in place. Two series of ducts 22 23, one series on each side of the ducts 21, extend from the chamber 6 to the ducts 21, the opposite ducts 22 opening into the duct 21 at a point opposite each other. The pipes 23 extend up a short distance and then are curved and run along the top of the partition 7, resting thereon, to the other end of the tank. Thence the pipes 23 are bent up and extend to a height above the extreme height of the gasolene in the chamber 6.

A supply-pipe 25, connected with a suitable gasolene-supply, connects with the valve 26, which in turn is connected with an opening 27 in the tank. By this means gasolene is fed into the gasolene-chamber 6. A gasolene-gage 28, the construction of which is similar to that of an ordinary water-gage, is provided on the head 3. A gasolene-inlet 29 and an air inlet and outlet 30 are provided, respectively, in the head 3 into the chamber 6 and the chamber 18 in connection with this gage 28.

The operation of my apparatus is as follows: A quantity of gasolene is supplied to the chamber 6 through the pipe 25, valve 26, and inlet 27. The gasolene entirely covers the carbureter 20 and covers the pipes 23 as they extend from the carbureter up along the partition 7. The upturned ends of the conductor-

pipes 23 extend up through the body of gasolene toward the top of the chamber 6. From an air-compressor a quantity of air under pressure is forced through the supply-pipe 9 into the air-chamber 5. From this chamber 5 the air passes to the pipe 12, thence through the pipe 13, the vertical check-valve 15, through the pressure governor or reducer 16, through the pipe 17 into the chamber 18 in the head 3. From this chamber 18 the air enters the carburetor through the inlet 19. Small streams or currents of air are forced from the chamber 20' of the carburetor through the respective ducts 21 into pipes 23. As the air-currents pass through the ducts 21 streams of gasolene are drawn into the ducts 21 through the ducts 22, and the air and gasolene are thoroughly intermingled in the pipes 23 and the air thoroughly carbureted. It will be seen that by this construction the air streams or currents are substantially surrounded by gasolene at the point of the introduction thereof, and the rapid evaporation of the gasolene and carburization of the air reduce the temperature of the air and gasolene below the freezing-point, and the vapor formed, though very rich, is a fixed gas and will not deteriorate by any change in the atmospherical conditions, as heat will expand the same, but will not separate the vapor into its constituent parts, and if the vapor were again cooled it would be found to be in the same condition as when formed.

Having thus described my invention, I claim as new and desire to secure by Letters Patent—

1. In a gas apparatus the combination with means for holding or supplying air under pressure, of means for holding a supply of gasolene or volatile fluid, a carbureter having a chamber 20', air-ducts connected therewith, ducts connected with said gasolene-supply and with said air-ducts and adapted to substantially surround the stream or current of air in each of said air-ducts with gasolene at the point of juncture between said air-ducts and gasolene-ducts, and means whereby said air is thoroughly carbureted and carried to a supply chamber or pipe, substantially as described.

2. The combination, in a gas apparatus, of means for holding or supplying air under pressure, means for holding a supply of gasolene or volatile fluid, a carbureter having a chamber 20' and provided with ducts 21 and 22, pipes 23 connected with said ducts 21 and extending above the supply of gasolene in said gasolene-supply, and a supply-pipe connected therewith, substantially as described.

3. The combination, with means for holding or supplying air under pressure, of a tank divided into two compartments 5 and 6 and having heads 3 and 4, said air-supply connected with said compartment or chamber 5, a second pipe 12 leading from said chamber 130

5 and connected with a carbureter 20 having
ducts 21 and 22, said ducts 22 connected with
said gasolene-supply and opening into said
ducts 21, pipes 23 connected with said ducts
21 and extending above the level of the gaso-
lene in said chamber 6, a supply-pipe 25, and
a service-pipe 11, substantially as described.

In testimony whereof I have hereunto set
my hand this 31st day of May, 1898.

ARTHUR M. LARA.

In presence of—

FREDERICK S. LYON,
THOS. F. BOWES.
